United States Patent Office

Des. 186,844
Patented Dec. 15, 1959

186,844

REAR VIEW MIRROR

George W. Walker, Bloomfield Hills, Mich., assignor to Ford Motor Company, Dearborn, Mich., a corporation of Delaware

Application June 25, 1958, Serial No. 51,535

Term of patent 7 years

(Cl. D14—6)

Fig. 1 is a perspective view of a rear view mirror showing my new design.

Fig. 2 is a side elevation thereof;

Fig. 3 is a front elevation thereof; and

Fig. 4 is a plan view partially broken away to illustrate the mirror position therewithin.

I claim:

The ornamental design for a rear view mirror, as shown.
